(57) **CLAIM**

The ornamental design for a slipper, as shown and described.

DESCRIPTION

FIG. 1 is a front, left and top perspective view of a slipper, showing my design.

FIG. 2 is a front elevation view thereof.

FIG. 3 is a rear elevation view thereof.

FIG. 4 is a left side elevation view thereof.

FIG. 5 is a right side elevation view thereof.

FIG. 6 is a top plan view thereof; and,

FIG. 7 is a bottom plan view thereof.

A slipper for the right foot is a mirror image of the slipper for the left foot as shown in FIGS. 1 to 7 and is also claimed.

1 Claim, 7 Drawing Sheets

FIG.1

FIG.2

FIG.3

FIG.4

FIG.5

FIG.6

FIG.7
